UNITED STATES PATENT OFFICE

146,192

DESIGN FOR A WRAPPING PAPER OR THE LIKE

Roger E. Sachs, San Francisco, Calif., assignor to Koret of California, Inc., San Francisco, Calif.,
a corporation of California

Application May 21, 1946, Serial No. 129,949

Term of patent 7 years

(Cl. D59—2)

To all whom it may concern:

Be it known that I, Roger E. Sachs, a citizen of France and a resident of the city and county of San Francisco, State of California, have invented a new, original, and ornamental Design for a Wrapping Paper or the like, of which the following is a specification, reference being had to the accompanying drawing, forming a part thereof.

The drawing is a plan view of a piece of wrapping paper or the like, showing my new design.

A full width of the wrapping paper or the like is disclosed vertically on the drawing. The design unit shown repeats horizontally on the drawing as indicated.

While the design disclosed herein is shown applied to wrapping paper or the like, it obviously may be applied to other similar materials such as textile fabrics.

I claim:

The ornamental design for a wrapping paper or the like, substantially as shown and described.

ROGER E. SACHS.
